UNITED STATES PATENT OFFICE.

GEORGE E. GOUCHER, OF PHILADELPHIA, PENNSYLVANIA, ASSIGNOR TO
JOHN C. GRAHAM, OF SAME PLACE.

DESIGN FOR FRINGE.

SPECIFICATION forming part of Design No. 13,086, dated July 25, 1882.

Application filed June 16, 1882. Term of patent 14 years.

To all whom it may concern:

Be it known that I, GEORGE E. GOUCHER, of the city and county of Philadelphia, in the State of Pennsylvania, have invented and produced a new and original Design for Fringe, of which design the following is a specification.

The accompanying drawing is a side view of a section of fringe embodying and illustrating my design, which consists in a fringe having a heading, A, to which is attached a series of chenille pendants, B, which are ornamented by being formed of warp-threads of distinctly different colors in the upper and in the lower portions of their lengths, respectively—that is to say, the upper portions, b, of the pendants, extending from the heading to the middle of the pendant, are of one selected color—as red—

and the lower portions, b', extending from the middle to the free end, are of a different color—as yellow—the result of such disposition of the differently-colored warp-threads being to present the appearance or effect of two broad bands or stripes upon the length of the fringe.

I claim—

A design for fringe, consisting of pendants formed of warp-threads of different colors in the upper and in the lower portions of their lengths, respectively, so as to present the effect of two broad bands or stripes upon the length of the fringe.

GEORGE E. GOUCHER.
